UNITED STATES PATENT OFFICE.

WILLIAM H. KIRNAN, OF BAYONNE, NEW JERSEY.

ALARM SYSTEM.

No. 911,016.

Specification of Letters Patent.

Patented Jan. 26, 1909.

Application filed July 30, 1908. Serial No. 446,037.

To all whom it may concern:

Be it known that I, WILLIAM H. KIRNAN, a citizen of the United States, residing at Bayonne, county of Hudson, State of New Jersey, have invented certain new and useful Improvements in Alarm Systems, of which the following is a full, clear, and exact description.

My invention relates to improvements in fire alarm systems and the like, and has for its object to provide a system for receiving simultaneously a number of signals from various sending stations connected by different circuits and to automatically transmit one of said signals to the various engine houses, meanwhile preventing the other signals which are being received from interfering with such transmission.

My invention further has for its object to provide means whereby such signals can be transmitted to the engine houses over a joker line or a gong line, or simultaneously over both the joker line and the gong line, and also provide means whereby the apparatus normally on the gong line can be switched onto and actuated through the joker line and signals sent to either the joker apparatus or gong apparatus at separate times without confusion. This is in case of the gong line being broken and inoperative.

It further has for its object to accomplish similar results by switching the joker apparatus over on the gong line in cases where the joker line is broken or inoperative. The joker apparatus is the apparatus which normally receives automatic calls. The gong normally responds to signals sent manually from the central station.

Another object of my invention is to provide for the manual transmission of a signal from the central receiving station to the various engine houses and to prevent the automatic transmission from interfering with the manual transmission.

The following is a description of my invention, reference being had to the accompanying drawings, in which—

Figure 1 shows the receiving and transmitting apparatus of the central station and the receiving apparatus in one engine house, together with the circuits connected thereto. Figs. 1^a, 1^b, 1^c, 1^d, 1^e show details. Fig. 2 shows a modification of the manual transmission apparatus and engine house apparatus, together with a modified circuit arrangement. In this form the current is re-

versed for operating the gong. Fig. 3 shows modifications of the central station receiving and transmitting apparatus. Fig. 4 shows a modification of the system, so as to adapt it to repeating signals to several stations without the assistance of an attendant. Fig. 5 shows a modified detail of the system of Fig. 1. Figs. 6 and 7 are diagrams.

Referring more particularly to the drawings, Figs. 1, A' A² A³ are three pairs of central station relay magnets, connected to separate local alarm circuit terminals B' B', B² B², B³ B³, the respective pairs of terminals being the terminals to which the alarm boxes and circuits are connected, one such circuit containing alarm boxes C' C' and battery C² being shown diagrammatically. Each of the relay magnets A' A² and A³ is provided with an armature and circuit controlling devices, the construction in each instance being the same. It will, therefore, be necessary to describe in detail the armature and circuit controlling devices of only one of these relays. In front of each of the relay magnets A' A² and A³ is an armature 1, rigidly secured to and carried by an arm 2, which arm is preferably rigidly connected to a shaft 3 supported by bearings 3' 3'. The arm 2 is normally retracted by a spring 4, and carries at its upper end a contact 5 insulated from the arm, which, when the arm is retracted, engages a contact 6, thereby establishing a recording circuit through the local recording instrument, this circuit being as follows: contact 5, contact 6, battery 7, starting magnet 8, recording magnet 9' controlling switch 10, contact 5. The contacts of the other relays corresponding to the contacts 5 and 6 are in multiple therewith, and the recording magnets 9² 9³ are also in multiple with one another. The controlling magnet 8 is, however, in series with all of the magnets 9' 9² 9³ and with the battery 7, so that it is energized whenever any one of the recording magnets is energized. The circuits from the alarm boxes C' through the several relay magnets A' A² A³ are normally closed, and the armatures 1 are therefore each normally attracted by its relay magnet so that the recording circuits are normally broken at their contacts 5—6. As a signal is sent in over an alarm circuit from one of the boxes C' for instance, the relay magnet A' causes the arm 2 to vibrate and thus energize the starting magnet 8 and the recording magnet 9', which acts to record the number of im-

pulses and hence the signal received from the box in the well known way by the recording device 11.

Loosely mounted upon the shaft 3 is a second arm 12, which lies between the magnet A' and its armature 1, or so as to be moved by the armature 1 when it is attracted by its relay magnet A'. This arm 12 has connected to it a retracting spring 13 and carries at its upper end an insulated spring contact 14, which engages a stationary contact 15, the contacts controlled by the several other relays corresponding to 14-15 being connected in series therewith and with one another and with a repeating or transmitting and controlling relay 16 and battery 17. The repeating circuit controlled by these contacts is as follows: battery 17, magnet 16, conductor 18, contact 14, stationary contact 15, conductor 18', contact 14', contact 15', and so forth, back to battery 17. The contacts 14 and 15 etc. are normally closed, so that the magnet 16 is normally energized and its armature attracted. If for any reason it is desired to cut out of service one set of the relay magnet contacts, such as 14-15, without disturbing the other parts of the system, this can be done by closing the switch 19.

6^a and 15^a are back stops limiting the movements of arms 2 and 12.

Whenever one of the relays A' A² A³, for instance A', is deenergized and its armature 1 retracted, the arm 12 being thereupon free to move, breaks the circuit through the magnet 16 at the contacts 14 and 15. When the circuit through the magnet 16 is thus broken, the magnet becomes deenergized, and its armature 20, which operates an arm 21, rigidly secured to a shaft 22, is retracted by its spring 23. The shaft 22 is thereby rotated slightly and the spring pawls 24 are drawn back so as to release the rear ends of interlocking or controlling levers 25, mounted in bearings 26. These controlling levers have springs 27, which, when their rear ends are released by the pawls 24, cause their front ends to move upwardly so as to pass behind the lower ends of the arms 12, when the arms 12 (as shown in Fig. 1^a) are held up by the armatures of the magnet. When, however, any relay magnet A' A² A³ is deenergized so that its armature 1 is not held up by the magnet, but is retracted by its spring 4, the lower end of the arm 12 moves above the outer end of the lever 25, (as shown in Fig. 1^c) thereby preventing the upward movement of the outer end of the lever 25, which would otherwise take place by reason of the spring 27. The result is, that when a signal is being received by the relay A'; for instance, the relay A' becomes deenergized, so that its armature 1, together with the arms 2 and 12, is retracted. The circuit through the magnet 16 is thereby broken at the contacts 14 and 15,

and the armature 20 released so that the detents 24 are withdrawn. The arm 12 of the relay A' being retracted, prevents any movement of the lever 25, while the corresponding arms of the other relays are not retracted, 70 because those relays which are energized do not interfere with the movement of their lever 25, and the forward ends of those levers therefore rise so as to come behind the lower ends of those arms 12 and prevent their acting until the levers 25 are re-set, the period being long enough to enable the street box C' to finish sending in its signal.

It is to be noted that the magnet 16 is controlled by the several arms 12, and that the recording magnets 9' 9² 9³ are controlled respectively by the arms 2. The arms 12 can be locked out of action, as above described. The arms 2, however, are all of them free to respond to whatever impulses are received 85 from the alarm boxes. If a signal is being received from only one alarm box, the arm 12 will actuate the relay magnet 16 accordingly, and the arm 2 will actuate the corresponding recording magnet 9' 9² 9³. If after 90 the first signal has started, another signal is sent in from another alarm circuit, for instance the alarm circuit of relay A², the arm 12' of that relay will be locked out of action, but the arm 2 will be actuated so as to record 95 the signal through the recording apparatus 9². If two signals should be sent in simultaneously over two separate signal circuits, so that the relays A¹ and A², for instance, are simultaneously energized and deenergized, 100 the arms 2 and 12 of both of these relays will act in unison so long as the impulses which they receive are in unison. When, however, these impulses get out of unison, the relay magnet which next receives an impulse is automatically locked out of action, because that impulse will move its lever 12 so as to permit the corresponding lever 25 to rise behind it, that lever being free to act, because the magnet 16 is still deenergized on account 105 of its circuit being broken at the relay A' and the spring pawls being thereby retracted. Both relays, however, as above described, will continue to record their signals to their respective recording apparatus. 110

The recording apparatus has a shaft 28 driven by any convenient power 29 and carrying a screw-thread 30 which engages a tooth 31 carried by an arm 32 pivoted in a bearing 33, which in turn is carried by a shaft 120 34. A spring 35 tends to draw it toward the screw 30 and a spring 36 tends to draw it toward the right hand end thereof, this movement being permitted by the mounting above described. The arm 32 also carries a projection 37, which, when the tooth 31 engages the left hand end of the screw 30, is engaged by a locking lever 38, which engagement arrests the movement of the shaft 28. When the starting magnet 8 is energized, a pin 39, 125

actuated by its armature, engages a beveled projection 40 carried by the arm 32, and forces the arm 32 backward, so that the finger 31 disengages the screw 30. The arm 32 is then moved to the right by the spring 36 and the arm 37 disengages the locking lever 38. The shaft 28 thereupon at once begins to revolve, and, together with the ink rollers mounted thereon, continues to revolve until 10 automatically stopped. After the finger 31 has been withdrawn from the screw-thread 30, and the spring 36 has drawn it to the right, it again engages the screw-thread 30. Whenever the magnet 8 is deenergized or energized, it is again withdrawn, so that it does not remain in engagement with the screw 30 for any considerable time, unless the magnetic condition of the magnet 8 remains unchanged for a considerable time. When the 20 magnetic condition of the magnet 8 does remain unchanged for a considerable time, a condition which arises when no signal is being sent in from an alarm box, or when an alarm box circuit has been broken, the finger 25 31 remains in engagement with the screw 30 for a period during which the screw 30 will move the lever 32 to the left until the locking lever 38 engages the projection 37, which will result in the stopping of the shaft 28 and 30 also result in causing the cam surface 37^a (Figs. 1, 1^c) to engage contact 41 and thereby close a local circuit at the contacts 41 and 42 for the purpose hereinafter described. The cam surface 37^a releases the contact 41 before 35 the lever 38 engages the projection 37. During the interval between the sending in of two signals from the alarm boxes, the magnet 8 will be deenergized. If an alarm circuit is broken, the magnet 8 will be energized 40 until the fault is corrected. Whether the magnet 8 be energized or deenergized for considerable periods, its failure to change the magnetic condition will result in the stopping of the shaft 28 in the manner above described. If the circuit from an alarm box is 45 interrupted, that will be evident upon the condition of its relay, and the attendant can interrupt the local circuit through the corresponding recording magnet by opening the 50 switch 10.

In order to automatically re-set the levers 25 when one signal is being recorded by the recording apparatus 9¹ 9² 9³, I provide a resetting relay magnet 43 in the local circuit 55 having a battery 44. This relay magnet actuates an armature 45, which is rigidly connected to a shaft 46, which carries depending arms 47—47. These arms are adapted to engage respectively with set-screws 48 and 49, the first being carried by the arm 12 and the second being carried by a projection on the lever 25. The armature 45 is normally retracted by the spring 50 so as to hold the depending arms 47 away from the 60 set screws 48 and 49. When the local cir-

cuit of the magnet 43 is closed at the contacts 41 and 42, by the cam surface 37^a on the projection 37 the armature 45 is attracted and the arms 47 are brought into engagement with their set screws 48 and 49 70 so as to force the lower ends of the arms 12 outward against the action of their springs 13 and force the inner ends of the lever 25 upward against the action of their springs 27. When the ends of the lever 25 are forced 75 upwards, the spring pawls 24 yield so that the inner ends pass above them and are retained thereby. The apparatus is thereby re-set in condition to receive further signals.

In series with the battery 17 is a tell-tale 80 recording magnet 51, which actuates a recording armature 52 and records every time the circuit to the battery 17 is interrupted, thus recording all the operations of the relay magnet 16 and its armature. The movements of the armature 20 of the relay 16 correspond to and control the signals which are automatically sent from the main central station to the engine houses. The magnet 51 thereby records all the signals which 90 are automatically transmitted to the engine houses. The transmission of the signals to the engine houses is brought about by the opening and closing of a transmission circuit controlled by the joker circuit contacts 95 53 and 54, the latter being moved into and out of engagement with the former by an anti-friction roller 55 carried on the upper end of the arm 21. The contact 53 is electrically connected with a switch arm 56, 100 which normally bears upon a contact electrically connected by a conductor leading to the switch arm 57 and to another contact 121. The switch arm 57 bears upon a contact which is electrically connected to the winding of a relay 58, and through it to the winding of a polarized relay 59, which in turn is connected to a contact 60, upon which bears the switch arm 61. The switch arm 61 is connected to a contact 62 upon which bears 110 a switch arm 63, which is electrically connected by the conductor 64 of a contact 65. This contact 65 makes and breaks engagement with a contact 66, which is connected to stationary contacts 67 and 68. From the 115 contact 67 the circuit normally passes through the pivoted member 69, which by the spring 70 is held in normal engagement with the contact 67. Thence the circuit passes through the battery 71, movable contact 72, which by the spring 73 is held in engagement with a conducting member 74. This conducting member is carried by an armature 75, which is retracted by a spring 76 whenever the magnet 77 is deenergized. 120 From the member 68 the circuit passes by the conductor 78 back to the movable contact 54.

The polarized armature 79 of the relay 59 is in series with a battery 80 and with an arma- 130

ture 81 of the relay 58. The armature 79 is not spring retracted and therefore remains against the terminal toward which it was last attracted. The armature 81 is retracted by a spring 82 and is normally in engagement with a back stop 83 making engagement with a contact 84 whenever the relay magnet 58 is deenergized. When the relay 58 is deenergized, the polarized relay 59 is also deenergized and its armature 79 is in engagement with a contact 85, which is in series with a joker bell magnet 86 actuating the bell armature 87. From the magnet 86 the circuit passes by the conductor 88 to the switch arm 89. Whenever the circuit is broken at the contacts 53 and 54, the circuit through the relay magnet 58 is broken, whereupon the spring 82 retracts the armature 81, causing it to engage the contact 84, and, since the armature 79 remains in engagement with the contact 85, a local circuit is completed through the joker bell magnet, as follows: battery 80, armature 81, contact 84, conductor 88, bell magnet 86, contact 85, polarized armature 79, back to battery 80. Whenever, therefore, the circuit is broken at the contacts 53 and 54, the local circuit to the battery 80 actuates the hammer armature 87 of the joker bell. One signal which is received by the central station is therefore automatically sent over the joker circuit, and the joker bell is actuated accordingly.

The main gong bell magnet 90 has its circuit controlled by the gong circuit contacts 91-92, and is energized by the battery 93 in series therewith. The circuit from the contact 91 is as follows: contact 91, battery 93, switch arm 94, conductor 95, switch arm 96, contact 97, switch arm 98, switch arm 99, conductor 100, gong magnet 90, conductor 101, contact 102, switch arm 103, contact 104, switch arm 105, to contact 92. In order to provide for the making and breaking of the circuit at the contacts 91-92, a manually controlled mechanism is provided consisting of a train of gears 106-107, geared to an escapement wheel 108, the train being driven by any suitable means. On the shaft of the gear 107 is mounted a removable signal wheel 109, having projections which engage the beveled end of the contact 91, so as to force it downward and cause it to make engagement with the contact 92, the engagements corresponding to the number of projections upon the wheel 109, and sending a signal to the main gong accordingly, the signal sent by the present wheel corresponding to the number thirty-two.

110 is the actuating handle of the manual transmitting mechanism, which when drawn downward, stores up the power for actuating the train. To this handle 110 is connected an arm 111, which has a contact controlling arm 112. This contact controlling arm,

when the handle 110 is in the normal position, bears against contact 113 and separates it from the contact 114, for the purpose herein-after described. The wheel 106 carries a projection 115, which when the wheel 106 is in normal position, engages the under side of the contact 65 and causes it to make engagement with the contact 66, for the purpose hereinafter specified.

When it is desired to manually transmit any particular number to the main gongs of the engine houses, a signal wheel 109 having the proper number of projections is selected and placed upon the shaft of the wheel 107. The handle 110 is then pulled downward and the signal wheel closes the circuit between the contacts 91 and 92, which establishes a circuit through the battery 93 and the gong magnet 90, thus sounding the alarm on the main gong.

In order to make it possible to ring the main gong over the joker circuit in case the gong circuit becomes disabled, additional switch arms mechanically connected to the switch arms 89 and 103 are provided, and two switch arms 116-117 are provided with suitable contacts and conductors to establish the proper circuit connections. The switch arm 103 and its associated switch arms are moved to the right, as shown in Fig. 6, so that the switch arm 103 makes engagement with the contact 120. The switch arms 94 and 105 are moved so that they make engagements with the contacts 121 and 123, as shown in Fig. 6, and the switch arms 116 and 117 are moved so that the switch arm 116 makes engagement with the contact 118, as shown in Fig. 6. The switch arms 116-117 when they are moved so that the switch arm 116 rests upon the contact 118, causes the battery 119 to energize the magnet 77, when the contacts 113 and 114 come into engagement with one another upon the movement of the handle 110, with the result that the armature 75 is attracted. The armature 75 actuates the member 68, which is the movable portion of a circuit changer or reverser, reversing the terminals of the battery 71 with relation to the circuit containing the conductors 64 and 78 and the polarized relay 59. The movement of the switch arm 116 to the contact 118 thus reverse the polarity of the polarized relay 59 and causes its armature 79 to move over so as to engage the contact 85'. With the switches in the position last described, the circuit from the contacts 53 and 54 is the same as it was originally, except that the battery 71 has had its terminals reversed. The circuit from the contacts 91 and 92 controlled by the signal wheel, is, however, as follows: contact 91, battery 93, switch arm 94, contact 121, conductor 122, switch arm 57, relay 58, polar relay 59, switch arm 61, contact 123, switch arm 105, to contact 92 (see Fig. 6). When

the manual transmitting apparatus is in operation, the circuit through the contacts 53 and 54 is broken at the contacts 65 and 66, as above described, so that the automatic transmission 5 cannot interfere with a signal which is being manually transmitted. As the circuit is made and broken at the contacts 91 and 92, the polarized relay armature 79 having been shifted so as to engage the contact 85' by the movement of the switch arm 116, the joker relay 58, whenever it is deenergized so that its armature 81 engages the contact 84, closes a local circuit through the gong magnet 90, so that the gong is actuated 10 through the joker transmission lines. This local gong circuit thus established is as follows: battery 80, armature 81, contact 84, switch arm 89, gong magnet 90, contact 102, switch arm 124, contact 85', polarized armature 79, battery 80.

When it is desired to actuate the joker, or automatic apparatus, through the gong transmission lines, the switch arms 94 and 105 remain in the position shown in Fig. 1. The 15 switch arms 56, 63, 116 and 117 are moved downward, so as to engage the second pair of contacts, and the two sets of switch arms in the engine house are both moved to the right so as to engage their second set of contacts (see Fig. 7). When this is done, the 20 connections of the battery are reversed, as before, by the movement of the switch arm 116, and the switch arms 63, 56, 94 and 105 are all connected to the same pair of engine 25 house mains, namely, the gong mains. The circuit through these mains is as follows (see Fig. 7), beginning with the switch arms 63 and 94, to which the contacts 54 and 91 are respectively connected: switch arms 63 30 and 94, conductor 95, switch arm 96, contact 125, relay magnet 58, polarized relay 59, contact 60, switch arm 98, switch arm 99, contact 126, contact 120, switch arm 103, conductor 127, switch arms 105 and 56, to 35 which are respectively connected the contacts 92 and 53. As was the case when the gong line was broken, when the manual transmitter is actuated, the armature 79 of the polarized relay 59 has been shifted, so 40 as to engage contact 85', this being due to the movement of the switch 116 and the manual transmitter. The result is that whenever the circuit is made at the contacts 91 and 92 by the signal wheel 109, the armature 55 81 of the relay magnet 58 is attracted, and whenever the engagement is broken at the contacts 91 and 92, the armature 81 is released so that it makes engagement with the contact 84, establishing a local circuit in 60 which the battery 80, relay armature 79, contact 85 and gong magnet 90 are included.

When the manual transmitting apparatus is not being used, the circuit through the relay magnet 58 is opened and closed at the 65 contacts 53 and 54, and since the reversing

magnet 77 is cut out of action at that time by the disengagement of the contacts 113 and 114, brought about by the projection 112, the polarized relay armature 79 is in engagement with the contact 85, with the 70 result that the battery 80, when the armature 81 engages the contact 84, is in circuit with the joker magnet 86 instead of with the gong magnet 90. The result is, that the signals which are transmitted automatically 75 through the engagement and disengagement of the contacts 53 and 54 are received by the joker.

When the manual transmission mechanism is being used, the first movement of the 80 handle 110 results in permitting the contacts 113 and 114 to come together so as to close the circuit through the reversing magnet 77. As soon as the train in the manual transmission mechanism starts up, the rod 115, 85 which is carried by the first wheel 106, leaves the contact 65 so as to permit it to separate from the contact 66. This is for the purpose of preventing a preliminary or false blow, such as would otherwise occur when the switch 90 arm 117 was moved out of engagement with the contact on which it rests, as shown in Fig. 1. This is prevented by the engagement of the contacts 65—66, because such engagement short circuits the switch arm 117. Therefore the movement of this arm when the contacts 65—66 are in engagement, does not produce any effect upon the circuit, of which the conductors 64 and 78 form branches, since the movement does not open the circuit through the battery, that being maintained closed by the contacts 65 and 66. 95

In order to prevent the system being permanently disturbed by the accidental or malicious interruption of the alarm circuit 100 which energizes the several relays A', A², A³, a pawl 128 is provided having two arms, one of which, 129, rests on the upper end of the arm 2 when the armature 1 is attracted by the relay. The other arm, 130, extends over 110 the upper end of the arm 12, and has a depending projection which is held away from the arm 12 when the arm 2 engages the under side of the arm 129, but moves downward so as to engage the upper end of the arm 12 115 when the arm 2 is retracted by its spring 4. The result of this is that when the relay A' is deenergized for an unduly long period, as would be the case when the alarm circuit was accidentally or maliciously interrupted, 120 the arm 12, when it is restored to normal position by the action of the magnet 43 upon the closing of the contacts 41 and 42, will be caught by the projection on the arm 130, and held in such normal position, the arm 2 permitting the pawl 128 to act in this manner, since it will remain in retracted position on account of the magnet A being deenergized. The fact that the magnet A' is abnormally deenergized will therefore not interfere with 130

the operation of the other parts of the system. The circuit through the recording magnet 9' will be closed, but this will not produce any disturbance, and moreover, as soon as the abnormal condition is observed, the attendant will open that circuit manually at the switch 10. In order that the arm 12 shall be brought up to the proper position by the armature 1 when the magnet 10 A' is energized, an adjusting screw 131 passing through the armature and bearing against the arm 12 is provided.

53^a and 54^a are auxiliary contacts which are controlled by the arm 21 of the relay 16, for such use as may be desired. It is to be noted that these contacts are separated when the magnet 16 is energized, and engaged when the magnet 16 is deenergized.

In Fig. 2, I have shown a slightly different arrangement of manual transmission mechanism and engine house mechanism and circuits, in combination with an automatic signal transmitting circuit operated by the central station apparatus shown in Fig. 1. In this figure, contacts 53 and 54 and anti-friction roller 55 correspond to parts similarly lettered in Fig. 1. The contacts 91 and 92 and the manual transmitting mechanism, including train 106, 107 and 108, signal wheel 109, handle 110, projection 111, pin 112 and contacts 113 and 114, also correspond to parts similarly lettered in Fig. 1. When the handle 110 is drawn down, the pin 112 moves from beneath the contact 113, permitting the contacts 113 and 114 to come into engagement and thereby short-circuiting the contacts 53 and 54 when the switch 132 is closed. The switch 132 is open when the system is in normal condition. When the system is in normal condition, the circuit beginning at the contact 53 is as follows: contact 53, contacts 133 and 134, battery 135, contacts 136 and 137, conductor 138, switch arm 139, conductor 140, switch arm 141, polarized relay 142, relay magnet 143, switch arm 144, conductor 145, switch arm 146, contact 54. When a signal is sent out by the manual apparatus, the circuit between the contacts 91 and 92 is as follows: contact 91, battery 147, switch arm 148, conductor 149, switch arm 150, conductor 151, switch arm 152, switch arm 153, gong 154, switch arm 155, switch arm 156, contact 92.

The circuits between the contacts 53 and 54 and between 91 and 92 above described, are entirely independent, and when the system is in normal condition, automatic signals can be sent to the joker by the automatic central station apparatus, and to the gong by the manual transmission apparatus without in any way interfering with one another.

In case either the gong circuit or the joker circuit is interrupted, so that it is necessary to use one of those circuits for transmitting

signals to both the joker apparatus and to the gong, this can be done and the automatic signal can be prevented from in any way interfering with the signal which is being manually transmitted. If the gong circuit is broken, the switch 153 and the three other switch arms connected thereto are thrown to the right, so as to engage the other contacts. The switch arms 148 and 156 are thrown downward and the switch 132 is closed. The closing of the switch 132, as before described, short-circuits the contacts 53 and 54 as soon as the arm 110 is pulled. By the arrangement just referred to the automatic transmission apparatus is cut out, so that as soon as manual transmission is begun, the automatic signal cannot break in upon the manual signal. With the switch arms in the position just described, the circuit between the contacts 91 and 92 is as follows: contact 91, battery 147, switch arm 148, contact 157, conductor 158, reversing magnet 159, contact 160, contact 92. Whenever the circuit just described is closed, the magnet 159 is energized, operating a reversing switch, the action being to raise the contact 137 so that it disengages the contact 136 permitting that contact to make engagement with the contact 133^a and at the same time engaging contact 134 and causing it to break engagement with contact 133. This reverses the terminals of the battery 135, which is in series with the polarized relay 142 and the relay magnet 143. The relay magnet 143 is not affected by this reversal, but the polarized relay 142 is so energized by the reversal that its armature 160 is withdrawn from the contact 161 and brought into engagement with the contact 162. When the circuit at the contacts 91—92 is broken, the magnet 159 is deenergized and the reversing switch being restored to its normal condition, the polarity of the battery 135 is again reversed, which results in restoring the armature 160 to its former position in engagement with the contact 161. Whenever the armature 160 engages the contact 162, a circuit is completed through the battery 163 and the gong magnet 154, the result being that the gong magnet 154 is energized so as to cause the gong to ring for every other reversal of the battery 135. The gong is therefore rung by sending reversed currents over the joker circuit, which reversed currents, since they affect or actuate only the polar relay, do not actuate the joker apparatus 173.

When the joker line is out of condition so that the joker has to be actuated over the gong circuit, both sets of engine house switches are thrown to the right, the switches 139, 146, 148 and 156 are all thrown down, and the switch 132 is closed. The closing of the switch 132 short-circuits the contacts 53 and 54 when the handle 110 is pulled, with the result above described.

When the other switches are in the positions just described, the circuit between the contacts 53 and 54 is as follows: contact 53, contacts 133 and 134, battery 135, contacts 5 136 and 137, conductor 138, switch arm 139, contact 164, conductor 149, switch arm 150, contact 166, relay magnet 143, polarized relay 142, contact 167, switch arm 152, switch arm 153, contacts 168 and 169, switch arm 10 155, contact 170, switch arm 146, contact 54. The opening and closing of the contacts 53 and 54 will thus energize and de-energize the relay magnet 143. As the magnet 143 is deenergized, its armature 171 will 15 engage the contact 172 and make and break the local circuit through the battery 163 and the joker magnet 173, thereby causing the joker bell to ring in accordance with the signal which is being automatically transmitted 20 by the making and breaking of the contacts 53 and 54.

When a manual signal is being transmitted from the parts in this direction, the circuit between the contacts 91 and 92 will be 25 as follows: contact 91, battery 147, contact 157, conductor 158, reversing magnet 159, contact 160, switch arm 156, contact 92. From this it results that every time the circuit is made or broken by the contacts 91 30 and 92, the magnet 159 is energized and de-energized so as to actuate the reversing switch heretofore described. This reverses the terminals of the battery 135, which are connected through the reversing switch and 35 the switch arms 139 and 146 with the terminals of the polarized relay 142, the circuit being easily traceable over the gong transmission lines. When the current energizing the polarized relay 142 is reversed by the 40 action of the reversing switch brought about by the engagement and disengagement of the contacts 91 and 92, the polarized armature 160 is made to engage and disengage the contact 162, as described, thus putting 45 the gong magnet 154 alternately in circuit and out of circuit with the battery 163 and energizing it so as to cause it to ring the main gong. By this means, in which reversing the current is relied upon to ring the 50 main gong whenever either the joker line or the gong line is temporarily or permanently disabled, I am again able to provide a system in which the automatic signals are prevented from breaking in upon any signals which are 55 being manually transmitted.

In Fig. 3, another arrangement of circuits and contacts for controlling the central station magnet 16 is shown. In this figure, that magnet is designated by the numeral 16', 60 and controlling contacts instead of being in series are in parallel. These contacts are normally out of engagement, with the result that the magnet 16' is normally deenergized, instead of being normally energized as in Fig. 65 1. The armature 174 is connected to the

shaft 22 and is retracted by a spring 175, which moves the shaft in the same direction in which it was moved by the magnetic attraction of the magnet 16 in Fig. 1. The spring contacts 176 are on the outside face 70 instead of the inside face of the arm 12 of Fig. 1 and engage contacts 177 when they are retracted. The result is that whenever the current of an alarm circuit is interrupted, contacts 176 and 177 are brought into engagement 75 and the magnet 16' energized and its armature attracted, the armature being retracted as soon as the alarm circuit is completed and the engagement between the contacts 176 and 177 again broken. The armature 174 actuates the contacts 53 and 54, producing the same results as were attained by the series arrangement of Fig. 1.

In Fig. 4, I have shown a modification designed to be used in systems where there is 85 no attendant at the central station and where the engine house apparatus and alarm sending apparatus are on one and the same circuit, and it is desired to repeat a signal sent in over one alarm circuit so that it may be 90 impressed upon all other circuits. In order to accomplish this, I use the central station mechanism and circuits shown in Fig. 1, with the addition of two contacts 178 and 179, which are controlled by the lever 25. When 95 the lever 25 is in normal condition, these contacts are held by it in engagement with one another. When the outer end of the lever 25 is lifted, the contacts 178 and 179 separate so as to break the circuit through 100 the corresponding relay magnets A' A^2 A^3 , and hence through the alarm circuit and the engine house gong. These contacts 178 and 179 are in parallel with other contacts 180 105 and 181, which are controlled by anti-friction rollers at the upper end of the arm 21. These contacts 180 and 181 are normally closed, but are opened whenever the magnet 16 is deenergized. As described in connection with Fig. 1, all the arms 12, with one exception, are automatically locked out of action and held out of action by the rising of the four ends of their respective levers 25. This results in the disengagement of the corresponding contacts 178 and 179, which throws 110 the corresponding circuits under the control of their contacts 180—181. Assuming that the relay A' is the one whose arm 12 is not locked out of position, it will be seen that the contacts 178—179 of that relay are held in 115 engagement, because the lever 25 is kept from moving. The arm 12 of the relay A' thus continues to vibrate and to open and close the circuit through the relay magnet 16, causing that magnet to hold its armature and 120 the anti-friction rolls 55 connected thereto. This movement opens and closes all the contacts 180—181 and thus repeats upon the idle combined alarm and engine house circuits 10 the alarm which is being transmitted 125 130

upon the combined alarm and engine house circuit of the relay A'.

Fig. 5 shows another modification, in which the shafts 22 and 46 are actuated by power mechanism which is electro-mechanically controlled. These shafts are provided with lever arms 183—184 at the upper ends of which are anti-friction rollers 185—186. These rollers are engaged by cams 187—188, which are independently driven from some sources of power, 189 and 190. 191 and 192 are two spring retracted pawls controlled by magnets 193 and 194, these magnets corresponding respectively to the magnets 16 and 43 of Fig. 1. The arm 183 also carries one or more anti-friction rollers 195, one of which corresponds to the anti-friction roller 55 of Fig. 1. The pawl 192 is normally drawn upward by the spring 196, so that its end is in the path of the outer pins 197 or projections on the cam 188. The magnet 193 is normally energized and the pawl 191 is thereby normally held in engagement with one of the outer stops 197^a on the cam 187, against the action of the spring 196^a. Whenever the magnet 193 is deenergized, the pawl 191 is drawn downward by the spring 196^a, permitting the pin 197^a to escape before the pawl 191 engages the next succeeding pin 198^a, so as to stop the cam. The cam thus revolves substantially one quarter of a revolution. When the magnet 193 is energized, the pawl 191 is drawn upward so as to lie in the path of the next succeeding pin 197^a, which stops the cam 187, after a very small portion of a revolution. The cam 188 is similarly controlled, except that it is released when the magnet 194 is energized and stopped when it is deenergized, as is evident from the arrangement of stops 197—198 shown in the drawings. The results attained are substantially the same as those attained in Fig. 1 having the advantage, however, that the apparatus is in part actuated and reset by mechanical power instead of by electrical power, which, in many instances, permits the attaining of greater certainty with less powerful electrical apparatus, and a smaller amount of electrical energy.

50 My invention permits of various other modifications and adaptations, such as will occur to those familiar with the art, and permits of the substitution of various equivalent devices for those which I have particularly shown and described and is, therefore, not limited to the precise construction or arrangement shown.

What I claim is:

1. In an alarm signal system, the combination of a plurality of central station relays, a plurality of local circuits connected to said relays respectively, a repeating relay, a plurality of pairs of contacts controlled by the central station relays and in circuit with the

winding of the repeating relay, locking levers, 65 restraining pawls for said levers disengaged therefrom on the movement of any of said pairs of contacts from their normal position, said levers when disengaged by said pawls holding from movement any corresponding 70 contacts then in normal position, and means for holding from movement the disengaged levers corresponding to any contacts not in normal position.

2. In an alarm signal system, the combination of a relay having an armature, a pair of contacts brought into engagement and disengagement by the movements of said armature at all times, a second pair of contacts mounted so as to be brought into engagement 80 and disengagement by the movements of said armature when said second pairs are not restrained, and means for restraining the relative movement of said second pair of contacts. 85

3. In an alarm signal system, the combination of a plurality of central station relays, an armature for each relay, a first set of contacts for each armature brought into engagement or disengagement by any movement of 90 said armature, a second pair of contacts for each armature, as to which the armature is relatively movable when said second contacts are restrained against movement, said armature acting to bring said second contacts into engagement or disengagement when not so restrained, recording circuits controlled by said first pairs of contacts, and a repeating circuit controlled by said second pairs of contacts. 95

4. In an alarm signal system, the combination of a plurality of central station relays, an armature for each relay, a first set of contacts for each armature brought into engagement or disengagement by any movement of 105 said armature, a second pair of contacts for each armature, as to which the armature is relatively movable when said second contacts are restrained against movement, said armature acting to bring said second contacts into engagement or disengagement when not so restrained, recording circuits controlled by said first pairs of contacts, a repeating circuit controlled by said second pairs of contacts, and means for locking in 110 normal position all of said second pairs of contacts which are in normal position when any one of said second pairs is out of normal position. 115

5. In an alarm signal system, the combination of a plurality of local circuits containing local alarm boxes C', a plurality of central station relay magnets connected thereto, an armature for each central station relay magnet, recording circuits controlled by said 120 armatures respectively, a repeating circuit controlled by each one of said armatures independently, and means for taking the re- 125

peating circuit out of the control of the other armatures when the movement of any one armature has disturbed its normal condition.

6. In an alarm signal system, the combination of a plurality of local alarm circuits, a plurality of central station relays controlled thereby, a plurality of recording devices controlled by said main central relays respectively, a repeating relay controlled by all of 5 said central station relays, engine house circuits controlled by said repeating relay, and means for automatically locking the repeating relay circuit against control by all armatures except any armature whose movement 10 has disturbed the normal conditions of said 15 circuit.

7. In an alarm signal system, the combination of a plurality of local alarm circuits, a plurality of central station relays controlled thereby, a plurality of recording devices controlled by said main central relays respectively, a repeating relay controlled by all of 20 said central station relays, engine house circuits controlled by said repeating relay, means for automatically locking the repeating relay circuit against control by all armatures, except any armature whose movement 25 has disturbed the normal conditions of said circuit, and means for releasing the locking 30 from time to time.

8. In an alarm signal system, the combination of a plurality of local alarm circuits, a plurality of central station relays controlled thereby, a plurality of recording devices controlled by said main central relays respectively, a repeating relay controlled by all of 35 said central station relays, engine house circuits controlled by said repeating relay, means for automatically locking the repeating 40 relay circuit against control by all armatures except any armature whose movement has disturbed the normal conditions of said circuit, and means for automatically restoring all parts to normal position from 45 time to time.

9. In an alarm signal system, the combination of a plurality of local alarm circuits, a plurality of central station relays controlled thereby, a plurality of recording devices controlled by said main central relays respectively, a repeating relay controlled by all of 50 said central station relays, engine house circuits controlled by said repeating relay, means for automatically locking the repeating 55 relay circuit against control by all armatures except any armature whose movement has disturbed the normal conditions of said circuit, resetting levers, a resetting magnet for actuating the same, and resetting contacts controlling said resetting magnet, and means for closing said resetting contacts 60 from time to time.

10. In an alarm signal system, the combination of a plurality of local alarm circuits, a

plurality of central station relays controlled 65 thereby, a plurality of recording devices controlled by said main central relays respectively, a repeating relay controlled by all of said central station relays, engine house circuits controlled by said repeating relay, 70 means for automatically locking the repeating relay circuit against control by all armatures except any armature whose movement has disturbed the normal conditions of said circuit, resetting levers, a resetting magnet 75 for actuating the same, and resetting contacts controlling said resetting magnet, said resetting contacts being controlled by the recording means.

11. In an alarm signal system, the combination of a plurality of central station relays having pivotally supported armatures 1 and contacts 5—6 controlled thereby, an independently movable arm 12 and contacts 14—15 controlled thereby, said arm 12 being 80 adapted to be moved in one direction by the armature 1, recording circuits controlled by the contacts 5—6, a repeating circuit controlled by the contacts 14—15, and interlocking mechanism acting on the arms 12. 90

12. In an alarm signal system, the combination of a plurality of central station relays having pivotally supported armatures 1 and contacts 5—6 controlled thereby, an independently movable arm 12 and contacts 14—95 15 controlled thereby, said arm 12 being adapted to be moved in one direction by the armature 1, recording circuits controlled by the contacts 5—6, a repeating circuit controlled by the contacts 14—15, interlocking 100 mechanism acting on the arms 12, and means for resetting the interlocks.

13. In an alarm signal system, the combination of a plurality of central station relays having pivotally supported armatures 1 and contacts 5—6 controlled thereby, an independently movable arm 12 and contacts 14—15 controlled thereby, said arm 12 being 105 adapted to be moved in one direction by the armature 1, recording circuits controlled by the contacts 5—6, a repeating circuit controlled by the contacts 14—15, interlocking mechanism acting on the arms 12, and means for resetting the interlocks and restoring said arms 12 to normal position. 110

14. In an alarm signal system, the combination of an automatic repeating relay, joker circuit contacts controlled thereby, a manual repeating apparatus, gong circuit contacts controlled thereby, a joker bell magnet, a 120 joker circuit controlled by said relay, a main gong magnet, a gong circuit controlled by said manual apparatus, and switches for operatively connecting said gong magnet and gong circuit contacts to said joker circuit. 115 125

15. In an alarm signal system, the combination of an automatic repeating relay, joker circuit contacts controlled thereby, a manual

- repeating apparatus, gong circuit contacts controlled thereby, a joker bell magnet, a joker circuit controlled by said relay, a main gong magnet, a gong circuit controlled by 5 said manual apparatus, and switches for operatively connecting said joker bell magnet and joker circuit contacts to said gong circuit.
16. In an alarm signal system, the combination of an automatic repeating relay, joker circuit contacts controlled thereby, a manual repeating apparatus, gong circuit contacts controlled thereby, a joker bell magnet, a joker circuit controlled by said relay, a main 10 gong magnet, a gong circuit controlled by said manual apparatus, and switches for operatively connecting said gong magnet and gong circuit contacts to said joker circuit, and for connecting said joker bell magnet 15 and joker contacts to said gong circuit as desired.
17. In an alarm signal system, the combination of an automatic repeating relay, joker circuit contacts controlled thereby, a manual repeating apparatus, gong circuit contacts controlled thereby, a joker bell magnet, a joker circuit controlled by said relay, a main gong magnet, a gong circuit controlled by 20 said manual apparatus, and means for automatically preventing the action of the automatic relay from interfering with signals sent by said manual apparatus when both are connected to the same circuit.
18. In an alarm signal system, the combination of an automatic repeating relay, joker circuit contacts controlled thereby, a manual repeating apparatus, gong circuit contacts controlled thereby, a joker bell magnet, a joker circuit controlled by said relay, a main gong magnet, a gong circuit controlled by 25 said manual apparatus, switches for operatively connecting said joker bell magnet and joker circuit contacts to said gong circuit, and means for automatically preventing the 30 action of the automatic relay from interfering with signals sent by said manual apparatus when both are connected to the same circuit.
19. In an alarm signal system, the combination of an automatic repeating relay, joker circuit contacts controlled thereby, a manual repeating apparatus, gong circuit contacts controlled thereby, a joker bell magnet, a joker circuit controlled by said relay, a main gong magnet, a gong circuit controlled by 35 said manual apparatus, switches for operatively connecting said gong magnet and gong circuit contacts to said joker circuit and for connecting said joker bell magnet and joker circuit contacts to said gong circuit as desired, and means for automatically preventing the 40 action of the automatic relay from interfering with signals sent by said manual apparatus when both are connected to the same circuit.
20. In an alarm signal system, the combination of an automatic repeating relay, joker circuit contacts controlled thereby, a manual repeating apparatus, gong circuit contacts controlled thereby, a joker bell magnet, a joker circuit controlled by said relay, a main gong magnet, a gong circuit controlled by 45 said manual apparatus, switches for operatively connecting said gong magnet and gong circuit contacts to said joker circuit, and means for electrically cutting out signals sent by the automatic relay when the manual apparatus is in action.
21. In an alarm signal system, the combination of an automatic repeating relay, joker circuit contacts controlled thereby, a manual repeating apparatus, gong circuit contacts controlled thereby, a joker bell magnet, a joker circuit controlled by said relay, a main gong magnet, a gong circuit controlled by 50 said manual apparatus, switches for operatively connecting said joker bell magnet and joker circuit contacts to said gong circuit, and means for electrically cutting out signals sent by the automatic relay when the manual apparatus is in action.
22. In an alarm signal system, the combination of an automatic repeating relay, joker circuit contacts controlled thereby, a manual repeating apparatus, gong circuit contacts controlled thereby, a joker bell magnet, a joker circuit controlled by said relay, a main gong magnet, a gong circuit controlled by 55 said manual apparatus, switches for operatively connecting said gong magnet and gong circuit contacts to said joker circuit and for connecting said joker bell magnet and joker circuit contacts to said gong circuit as desired, and means for electrically cutting out signals sent by the automatic relay when the manual apparatus is in action.
23. In an alarm signal system, the combination of an automatic relay magnet, joker circuit contacts controlled thereby, a manual transmission apparatus, gong circuit contacts controlled thereby, a joker magnet, a joker circuit, a gong magnet, a gong circuit, switches for connecting the gong magnet and gong circuit contacts to the joker circuit, a polarized relay controlling one of the bell 60 magnets, and means for reversing the current in said relay when the manual apparatus is actuated with the gong contacts operatively connected to the joker circuit or with the joker contacts operatively connected to the gong circuit.
24. In an alarm signal system, the combination of a plurality of central station relays, an armature for each relay, a first set of contacts for each armature brought into engagement or disengagement by any movement of said armature, a second pair of contacts for each armature, as to which the armature is relatively movable when said second contacts are restrained against movement, said 65 contacts

armature acting to bring said second contacts into engagement or disengagement when not so restrained, recording circuits controlled by said first pairs of contacts, a repeating circuit controlled by said second pairs of contacts, means for restoring each of said second pair of contacts to normal position when the magnetic condition of said relay is other than normal for a considerable period, and pawls adapted to retain any pair of contacts in normal position when restored during such a period, said armatures acting to withdraw said pawls when the magnetic condition of said relays again becomes normal.

25 25. In an alarm signal system, the combination of a plurality of central station relays, an armature for each relay, a first set of contacts for each armature brought into engagement or disengagement by any movement of said armature, a second pair of con-

25 tacts for each armature, as to which the armature is relatively movable when said second contacts are restrained against movement, said armature acting to bring said second contacts into engagement or disengagement when not so restrained, recording circuits controlled by said first pairs of contacts, a repeating circuit controlled by said second pairs of contacts, means for restoring each of said second pair of contacts to normal position when said relays become deenergized for a considerable period, and pawls adapted to retain any of said pairs in normal position when restored during such a period, said armatures acting to withdraw said pawls when the relays again become energized.
